UNITED STATES PATENT OFFICE.

ELWYN A. MALLORY, OF CINCINNATI, OHIO.

ADJUSTABLE HINGE.

SPECIFICATION forming part of Letters Patent No. 398,636, dated February 26, 1889.

Application filed October 29, 1888. Serial No. 289,365. (No model.)

To all whom it may concern:

Be it known that I, ELWYN A. MALLORY, a citizen of the United States, residing at Cincinnati, in the county of Hamilton and State 5 of Ohio, have invented a new and useful Improvement in Hinges, of which the following is a specification.

My invention relates to the common door, gate, and shutter hinges; and the object of my 10 improvement is to provide a hinge which is adjustable in two directions, so as to give each hinge on a door, &c., an equal amount of strain and bearing, and also to adjust the swinging part so as to fit exactly the opening 15 or place to be closed. I attain these objects by the mechanism illustrated in the accompanying drawings, in which—

Figure 1 is a section through my improved hinge. Fig. 2 shows a top view of it, and Fig. 20 3 shows the application of my hinge to an iron shutter.

Similar letters refer to similar parts throughout the several views.

My hinge is the reverse of the general type, 25 as the hinge-loop is secured to the frame and the hinge-pivot fastened to the swinging part.

The hinge-leaf *a* is formed at its inner end with a cylindrical screw-threaded stem, *h*, which is designed to be screwed axially into 30 one end of a cylindrical body, *b*, which is bored and screw-threaded for this purpose, said bore being enlarged at its inner end, so as to allow an easier tapping. The head of the body *b*, comprising the lugs *m* *n*, is bored and screw-threaded transversely thereof, and the screw-threaded stem *e* of the pivot-bolt or pintle *f* 35 screwed into it, said stem being left blank on its root, so as not to weaken it in its vital part,

is turned smooth and fits into the enlarged lower part of the hole. Integral with the pintle *f* is the collar *d*, forming a shoulder for the hinge-loop *g*, and, being hexagon-shaped on its upper part, allows an easy turning of said pintle. A lock-nut, *c*, bearing against the lug *m*, is designed to hold the pivot-bolt 40 in its vertical adjustment and keep it from turning by the moving door. The pintle *f* is turned smooth and fits and turns in the hinge-loop *g*, which is fastened to the door-frame, and can be made to suit the various purposes. 45

It is obvious that the construction can be modified in making either the hinge-pivot integral with the body *b* or the body *b* solid with the hinge-leaf *a*, which will make the hinge adjustable in only one direction. 50

Having thus described my invention, what I claim as new, and desire to secure by Letters Patent, is—

In a hinge, the combination of the leaf *a*, having a cylindrical screw-threaded end, *h*, 60 a cylindrical body, *b*, provided with a screw-threaded longitudinal bore to receive the screw-threaded end of the leaf, and provided also on its inner end with a head comprising the lugs *m* *n*, said head having a screw-threaded bore transversely thereof, a pivot-bolt, *f*, having a screw-threaded stem, *e*, designed to be screwed into the head of body *b*, a collar, *d*, integral with the pintle, a lock-nut, *c*, and a hinge-loop, *g*, all substantially as described. 65 70
